UNITED STATES PATENT OFFICE.

CHARLES E. CAMPBELL, OF LYNN, MASSACHUSETTS.

TRANSFORMER BELL DEVICE.

1,168,378.

Specification of Letters Patent. Patented Jan. 18, 1916.

Application filed September 2, 1915. Serial No. 48,626.

To all whom it may concern:

Be it known that I, CHARLES E. CAMPBELL, a citizen of the United States, residing at Lynn, in the county of Essex and 5 State of Massachusetts, have invented certain new and useful Improvements in Transformer Bell Devices, of which the following is a specification.

My invention relates to improvements in 10 transformer-bell devices, and the object of my improvement is to produce a device for door-bell use that receives current from service mains and which involves a minimum of skill for installation, particularly with 15 regard to the leads that connect with the operating switch or push button.

In the accompanying drawings, Figure 1 is a front elevation of my improved transformer-bell device, the cover being removed 20 from one of the bell members, disclosing the bell mechanism, and the electrical connections being indicated by broken lines. Fig. 2 is a rear elevation of the same. Fig. 3 is a 25 diagrammatic representation of the parts and the electrical connections.

My improved transformer-bell device comprises a base 10 on which are mounted a transformer 11 at the middle portion and a pair of bell members 12, one on each side 30 of the said transformer 11. The transformer 11 is inclosed in a suitable housing and comprises a pair of primary terminals in the form of leads 13 adjacent a pair of bushings 14, the free ends of which leads 35 may be connected to the service mains, and a pair of secondary terminals at the lower end which are connected to a pair of binding posts 15 and also to the bell members 12 in a special manner to be described. The 40 said binding posts 15 are exposed, suitably to receive the leads for a circuit from the transformer, which may be a diminutive heating coil, or a signal lamp, or other low voltage device. The bell members 12 comprise a bell base 16 on which is mounted the 45 usual bell mechanism having the usual internal connections, but which I have provided with a special arrangement of external connections in order to effect the purposes of my invention. The said mechanism 50 comprises the bell 17, the vibrating member 19, the magnet 20, and the contact post 21. The vibrating member 19 is supported by the post 22 at the lower end and comprises the armature 23 and contact arm 24 at the middle portion, and the hammer 18

at the upper free end. The magnet 20 comprises the U-shaped core 25 and the coils 26.

Various arrangements of details may be employed in operatively supporting the 60 parts of the bell mechanism mentioned, which involves a proper use of insulating materials. The magnet 20 and the adjacent parts I inclose within a cover 27 which is 65 of ordinary form construction and I provide a special arrangement of binding posts comprising one pair within the cover 27 and another pair without the said cover, and which are exposed and accessible. The pair of binding posts within the cover comprises a 70 right hand inner binding post 28 connected to the vibrating member 19 and a left hand inner binding post 29, connected to one end of the magnet coil 26. The other of the magnet coils 26 is connected to the contact 75 post 21. Thus the inner binding posts 28 and 29 constitute essentially the terminals 80 for what may be considered to be the bell structure proper 12, corresponding to the ordinary arrangement of the bell and mechanism therefor, which however differs from the ordinary arrangement in that the binding posts 28 and 29 thereof are under normal conditions covered and concealed, and substantially inaccessible. 85

Considering the outer or exposed pair of binding posts, these comprise the right outer binding post 30 which is common with the inner right hand binding post 28, being connected therewith by the lead 31, at the 90 rear of the base 10, and the left outer binding post 32. The said left outer binding post 32 and the left inner binding post 29 are connected by separate leads 33 with the secondary terminals of the transformer 11 95 and the binding post 15. The leads 33 are at the rear of the base 10, and concealed. The only exposed parts of the electrical connections are the transformer binding posts 15 which are alive and suitable for supplying current to special devices and the two pairs of bell binding posts 30 and 32, one for each bell member 12. 100

It will be noted that cross-connecting the bell binding posts 30 and 32 serves to close 105 the electrical circuit from the transformer 11 through the bell member 12, wherefore leads may be run therefrom to a circuit closing device, which would generally be in the form of a push button, at any 110 point desired to suit convenience. That is to say, a complete, uninterrupted lead will

connect each one of the binding posts 30 and 32 with one of the terminals of the push button on other form of current closing device, and for this reason the two leads 5 making the connections mentioned will be of the same length, thus permitting twin cord to be used for effecting such connections. The fact that twin cord may be used for effecting the connections between the bell 10 binding posts and the push button, and because there are no breaks or joints to make in effecting such connections the wiring to the push button may be effected with a minimum of danger or liability of error by help 15 such as is classed as unskilled.

At the upper end of the middle portion 20 of the base 10, above the transformer 11, is a terminal box 34 in the form of a border wall or barrier inclosing the portion of the base 10 which supports the bushing 14 and into which the transformer primary leads 13 project and which is suitable for housing the joints by which the said leads 13 and the service mains may be connected. 25 The branches from the service mains pass through the bushing 14, so that the lead or terminal box 34 dispenses with the usual terminal box adjacent the ends of the service branches. A cover 35 of insulating material may be provided for the terminal box 34, the same being held in place by suitable screws 36.

I claim as my invention:

1. In combination, a base having a terminal box, a transformer mounted on the

said base and having primary leads extending into the said terminal box, a bell member mounted on the said base, a pair of terminals on the said base suitable for being connected to a push-button, and connections 40 operatively connecting the said terminals with the secondary of the said transformer and the mechanism of the said bell member.

2. A unitary transformer bell device comprising a base, a pair of push-button terminals, supply terminals, a transformer, and a bell device supported by the said base, and connections interconnecting the said terminals, transformer, and bell device such that by supplying current to the said supply terminals the transformer will serve to operate the mechanism of the said bell member responsive to cross-connecting of the said push-button terminals.

3. A transformer-bell device comprising 55 a pair of supply terminals for being connected to service mains, a bell member comprising a bell and a pair of push-button terminals adjacent thereto, a transformer, and connections interconnecting the said terminals, bell member and transformer such that a push-button connected across the said push-button terminals will operatively connect the said bell member with the said transformer.

CHARLES E. CAMPBELL.
